CARTON LOADING MECHANISM

Alten E. Whitecar, Westville, N.J., assignor to Smith Kline & French Laboratories, Philadelphia, Pa., a corporation of Pennsylvania

Filed Oct. 8, 1962, Ser. No. 228,925

3 Claims. (Cl. 53—65)

This invention pertains generally to mechanism for the loading of cartons, and particularly to means associated with such loading mechanism to assure the actual loading of such cartons. The invention is particularly useful in connection with the rapid loading of cartons of small size, since in such instances the difference in weight between a loaded and an unloaded carton is often so small as not to be readily detected either manually or by other than the most sensitive weight responsive mechanism. It is, however, broadly applicable to the loading of cartons of any size with objects of any weight, thus avoiding manual or other time consuming inspection.

These and other features of the invention will become apparent to persons skilled in the art as the specification proceeds in connection with the drawing in which:

The single figure is a perspective view, shown broken, of a known type of carton loading mechanism with the invention shown in combination therewith.

Referring now more particularly to the drawing, at 10 is shown a conventional carton loading mechanism to which the invention is applied. Said mechanism is illustrated as having chains 11, 12, 13, 14 and 15. These chains have their ends connected together so as to be endless to form an endless conveyor construction, the top of which is caused to move to the left as seen in the drawing, e.g., by virtue of being actuated by sprockets of the same size (not shown) mounted on a single driven shaft (also not shown). Thus these chains rotate together in the same direction and at the same speed, much the same as endless belts, appropriate supports being provided at the points of turn. On chain 12 are mounted a plurality of spaced article orientation units 16, each so shaped as to form a receptacle 18 for an article to be packaged, the top and sides of said receptacle 18 but not its bottom being broken in continuity due to lateral slit 19 intermediate the ends of each unit 16, all slits 19 of said units 16 being in alignment. As will be seen hereinafter, the provision of slits 19 is a part of the invention.

Mounted on chain 13, and in line with units 16 are a plurality of spaced guide members 21 arranged to slide on spaced rails 22 and 23. As will be seen hereinafter, members 21 serve for holding the feeding ends of the cartons open and for guiding the articles into the cartons. Also, guide members 21 may be considered as continuations of receptacles 18, each alignment of a unit 16 and a member 21 being regarded as a single receptacle or transverse channel.

Members 24 are attached to chain 14 and have upright lugs 25 which form a plurality of carton receiving spaces 26, each such space 26 being lined up with a separate guide member 21 and its associated receptacle 18.

Positioned alongside and longitudinally of chain 15 is a stationary bar 27 on which end flaps 31 on the outer ends of cartons 32 slide, the remaining flaps on the outer ends of cartons 32 customarily being in closed position.

Positioned directly above the outer ends of guide members 21 is a stationary flat strip 33 on which end flaps 34 on the inner ends of cartons 32 slide, the two flaps 35 at right angles to each flap 34 being held in open position by overlapping the sides of the associated guide member 21.

In the operation of a conventional and well-known carton loading mechanism thus far particularly described, the articles 36 to be packaged which may be of any character, e.g., ampoules which are generally relatively small,

2

are fed into receptacles 18 either manually, but generally automatically by well-known means which, for the sake of brevity, are not shown. Likewise, cartons 32 are fed into carton receiving spaces 26, each with its flaps eventually positioned with respect to bar 27, strip 33, and its associated guide member 21 in the manner already described. Such latter feeding also may be done manually, but is generally accomplished automatically by well-known means, which also for the sake of brevity, are not shown.

10 The next step is to slide each such article 36 out of its respective receptacle 18 and through the associated guide member 21 into the carton 32 aligned therewith. This also may be done manually by an operator standing along- 15 side of the moving mechanism, a finger serving well for eventually tucking the article fully into its respective carton 32 from underneath strip 33 and out of the end of the associated guide member 21. In large scale packaging, however, this operation is usually performed automatically by well-known means which also, for the sake of brevity, are not shown in detail, but merely in part 20 illustrated as being comprised of a plurality of pusher arms 37 associated with chain 11, said pusher arms 37 being arranged to travel in unison with receptacles 18 and guide members 21, each pusher arm by cam actuation 25 progressively moving inwardly as the mechanism moves to the left as seen in the drawing, as is well understood by persons skilled in the art.

20 Bar 27 against which the outer end of each carton 32 abuts serves as a stop to prevent each article 36 from 30 projecting beyond the outer end of its carton 32.

Each carton 32 as it is filled, progresses to the left as seen in the drawing, and may be removed from the traveling mechanism either manually or automatically, such as 35 after having its ends closed by well-known mechanisms, not shown.

Coming now to the invention, a serious drawback in mechanisms of the kind described, and irrespective of whether the articles are advanced into the cartons manually or automatically, is that on occasion there is a failure to deposit an article 36 in each receptacle 18, whereupon in each such instance a carton remains empty. Due to the rapidity of operation of the loading mechanism, it is 40 very difficult for an operator to spot and mark such cartons for reject purposes. The problem becomes even 45 more serious when the loading is made entirely automatic. The result is that empty cartons may find their way into shipments of filled cartons which can become a very 50 serious matter, particularly in the field of pharmaceuticals, as can be well understood.

To guard against such contingency, the invention is directed to the automatic destruction of any carton that remains unfilled, so that such carton may be readily identified and rejected.

55 To this end, a sensing mechanism 41 is provided which in turn operates a carton mutilation mechanism 42 in the event that any receptacle 18 fails to receive the article to be packaged, the carton destroyed being that which would have been filled had the particular receptacle 18 received 60 the article.

Sensing mechanism 41 has a shoe 43 provided with an upwardly curved forward nose 44, said shoe being positioned in line with space 19 and dimensioned so as to be capable of moving downwardly therein. As shown, shoe 65 43 is attached to bar 45 which in turn is pivotally mounted at 46 on stationary plate 47. Plate 47 carries an electrical switch 48 having an actuating element 49 extending downwardly in contact with bar 45, as shown at a point offset somewhat from pivot 46.

70 Switch 48 is in a circuit which includes solenoid 51 of carton destruction mechanism 42, said solenoid being mounted on stationary bracket 52, and said circuit being

energized from any suitable electrical source, not shown.

Armature 53 of solenoid 51 is pivotally attached to lever 54 by a pin 55, lever 54 in turn being pivotally mounted on bracket 56 as indicated at 57, bracket 56 being shown as secured to the case of solenoid 51.

The non-pivoted free end of lever 54 carries a knife 58 for carton mutilation purposes should it develop that such carton will not be filled with an article because of the absence of such article in the receptacle 18 from which the carton is to be filled, such mutilation taking place automatically as will now be particularly described.

It is to be understood that when shoe 43 is in the position shown in the drawing, that is, when held up by one or for a short instant more than one article 36 in receptacles 18, switch 48 is open and the circuit through solenoid 51 is unenergized. Under such circumstances, armature 53 is retracted upwardly by virtue of a conventional inner construction of solenoid 51 that is spring biased upwardly, said solenoid being so selected, and lever 54, as a consequence is in its upward position to hold knife 58 upwardly to clear the cartons 32 passing thereunder.

As shown in the drawing, article 36a is about to pass out from under shoe 43, whereupon if it were not for the fact that article 36b is already, or is about to be, engaged by forward nose 44 of shoe 43, that is if the receptacle 18 containing article 36b were empty, shoe 43 would drop upon becoming free of article 36a to close switch 48. The closing of switch 48 would energize solenoid 51 causing its armature 53 to descend to depress lever 54, thereby causing knife 58 to cut into and mutilate or destroy carton 32b, this being the carton lined up with and to be filled by article 36b. Knife 58 may be positioned to cut into the top of carton 32b, or descend just in advance of carton 32b, in either case, due to the movement of the carton to the left relative to the knife, a cutting action due to such movement, by itself, will occur.

In any event, knife 58 remains depressed until such time that article 36c, the next in series reaches forward nose 44 of shoe 43 to raise shoe 43 thereby breaking the circuit through solenoid 51, whereupon knife 58 is raised free of carton 32c, to avoid cutting the latter carton, that is, all parts return to their original positions as shown. Forward nose 44 of shoe 43 is, of course, of such length that knife 58 is raised in time to clear carton 32c into which article 36c is to be inserted.

On the other hand, should the receptacle 18 shown as holding article 36c actually be empty, knife 58 would remain depressed to also destroy carton 32c as it moves relative thereto, as can be readily seen. Obviously, the same applies in the case of a series of empty receptacles 18.

Stationary laterally spaced bars 61, between which lever 54 is shown positioned, are arranged longitudinally of mechanism 10, and assist in holding cartons 32 in position, especially during any destruction thereof by knife 58. Bars 61 may also serve as a guide for lever 54 for stability purposes to avoid possible excessive sidewise movement. Although bars 61 may touch the tops of cartons 32, a clearance, e.g., a slight clearance, also is contemplated.

It will be appreciated that shoe 43 need not necessarily descend the full distance in space or slit 19 to operate switch 48, but just sufficiently to sense the absence of an article 36, depending upon the latter's diameter. Nor need slit 19 extend downwardly in a unit 16 the full distance of its side walls, but only sufficiently to permit operation of the sensing mechanism. With this in mind an adjustable stop is provided at 62 for shoe 43, this being shown as comprising screw 63 threadedly engaging stationary bracket 64, the end of screw 63 being positioned in the path of bar 45 to adjustably limit its downward movement depending upon the requirements of shoe 43 for sensing purposes.

It will, of course, be understood by persons skilled in

the art that switch 48 and solenoid 51 may be chosen to operate in an opposite manner from that particularly described in that switch 48 may be of the type to close upon the upward movement of shoe 43, and solenoid 51 of the type to retract its armature upward when energized by the closing of switch 48 to bring knife 58 up out of the path of cartons 32. With such arrangement, switch 48 would open upon the downward movement of shoe 43 to deenergize solenoid 51, whereupon lever 54 would drop to bring knife 58 into the path of cartons 32.

It will also be understood by persons skilled in the art that the switch and solenoid combination may be substituted by any other combination of control and motor mechanism known in the art, such as those operating by means of a fluid, e.g., air, instead of electrical energy, e.g., a piston and cylinder may be substituted for solenoid 51 and a valve for switch 48, the operation of which combination in its multitude of applications being so well understood as not to require further elaboration.

Cartons 32 may be of any composition capable of destruction by knife 58, of which the widely used cardboard or other paper-product cartons are examples.

It is to be understood that while it is highly preferred to position shoe 43 for upward and downward movement in a slit 19, this is not an absolute essential, for in the event that articles 36 are of a size and/or shape to project above receptacles 18, the position and/or shape of shoe 43 may be adapted for up and down movement above such receptacles for up and down movement of knife 58 in the manner described, as can be readily seen.

It hardly need be mentioned that articles 36 are of at least sufficient rigidity for shoe 43 to pass thereover in elevated position in the manner described.

Having particularly described the invention, it is to be understood that this is by way of illustration and not of limitation, for changes, omissions, additions, substitutions and/or other modifications may be made without departing from the spirit thereof. Accordingly it is intended that the patent shall cover, by suitable expression in the claims, the various features of patentable novelty residing in the invention.

What is claimed is:

1. In combination with packaging mechanism having conveyor means having receptacles for receiving and guiding articles to be placed in cartons, and members for receiving cartons aligned with said receptacles, the improvement comprising means for sensing the absence of an article in any receptacle, and means operatively connected to said sensing means for the mutilation of cartons aligned with empty receptacles, said sensing means comprising a sensing member mounted for downward and upward movement in response to the absence and presence respectively of articles in the receptacles and an electrical switch, said movement operating said switch, and the means for the mutilation of cartons comprising a solenoid electrically connected to said switch for operation thereby, a knife and means for connecting said knife to said solenoid for the downward and upward movement of said knife in and out respectively of the path of the cartons.

2. The combination of claim 1 wherein said knife is aligned transversely of said sensing member and said switch and said solenoid causes said knife to move downward and upward in unison with said sensing member.

3. The combination with mechanism for the continuous packaging of articles in cartons, said mechanism comprising a conveyor provided with a series of longitudinally spaced transverse channels for receiving and guiding articles to be packaged, means at the outlet ends of said channels for maintaining cartons in alignment therewith, said last-mentioned means including means for holding the inlet ends of said cartons open, means at the receiving ends of said channels for sensing the absence of an article in any said channel, and means at the outlet ends of said channels for the mutilation of the carton aligned

with any said last-mentioned channel upon operation of said sensing means, said sensing means comprising a shoe positioned longitudinally of said conveyor, a continuous longitudinal slit in said conveyor, said shoe being mounted for upward and downward movement in said slit, an electrical switch, means connecting said shoe to said switch for operation of said switch in response to movement of said shoe, said means for the mutilation of cartons comprising a solenoid, a lever positioned above said cartons, means for connecting said lever to said solenoid for upward and downward movement of said lever upon operation of said solenoid, a knife on said lever, said knife being positioned in transverse alignment with said shoe, and means for electrically connecting said

10 5

switch and said solenoid, the operation of said switch and said solenoid being coordinated to raise and lower said knife out of and into the path of said cartons in unison with the upward and downward movement of said shoe.
